UNITED STATES PATENT OFFICE.

JOSEPH R. STRETESKY, OF BONNE TERRE, MISSOURI.

HOT-AIR FURNACE.

1,325,421.

Specification of Letters Patent. Patented Dec. 16, 1919.

Application filed February 25, 1918. Serial No. 219,009.

To all whom it may concern:

Be it known that I, JOSEPH R. STRETESKY, a citizen of the United States, residing at Bonne Terre, in the county of St. Francois and State of Missouri, have invented certain new and useful Improvements in Hot-Air Furnaces; and I do declare the following to be a full, clear, and exact description of the invention, such as will enable others skilled in the art to which it appertains to make and use the same.

My invention relates to improvements in hot air furnaces of the type having a single main hot air outlet from the air heating casing into a room above, and cool air inlet means from this room into the casing. Heretofore, it has been possible to heat a number of communicating rooms by this kind of furnace, but impossible to heat others which do not communicate in some way with the one in which the register is located. It is therefore the object of my invention to so improve upon the furnace in question as to permit the heating of rooms, even though they be isolated from those into which the heat from the furnace is now discharged; and in this connection a further object is to provide a novel form of damper for controlling the discharge of heat.

With the foregoing general object in view, the invention resides in the novel features of construction and unique combinations of parts to be hereinafter fully described and claimed, the descriptive matter being supplemented by the accompanying drawings which form a part of this specification and in which:

Figure 1 is a perspective view with parts in section showing my improved features of construction for heating a room in the basement and a room above the basement;

Fig. 2 is a detail horizontal section on the plane of the line 2—2 of Fig. 1; and

Fig. 3 is a view similar to Fig. 1 but illustrating a modified form of the invention for heating rooms above the basement.

The numeral 1 designates a furnace proper or firebox which is surrounded by an air heating casing 2 having a main central outlet pipe 3 leading from its upper end to the central portion of a register 4 in the floor above. A cool air inlet pipe 5 surrounds the outlet pipe 3 and discharges at its lower end into the cool air inlet casing 6 which surrounds jacket 2 and supplies air to the latter. These features are all of well

known construction and form no part of my invention except in combination with the parts now to be described.

A branch hot air pipe 7 extends horizontally from the pipe 3 across the space between this pipe and the pipe 5 and discharges into a basement room R through its wall W. A cool air pipe 9 discharges into the lower end of the casing 6 and extends through the wall W. Hot air is adapted to travel through both of the pipes 3 and 7 and cool air enters through the pipes 5 and 9.

For controlling the discharge of hot air through the two pipes 3 and 7, a damper 10 is positioned in the pipe 3 and is pivotally mounted at the upper side of pipe 7 as shown at 11, said damper being adapted to swing downwardly to close the pipe 7, upwardly to close pipe 3, or to any one of a number of intermediate positions so that the escaping heat will be branched and directed through both pipes. The damper operates in the portion 12 of the pipe 3 and is provided with a suitable handle 13 on the exterior of said pipe. It will also be understood that any preferred locking means may be provided for holding the damper in adjusted position.

In Fig. 3, the construction of most parts is the same as in Fig. 1, but a branch hot air pipe 7^a extends from the pipe 3 to a register 8^a in a room above the furnace room and separate from the room in which the register 4^a is located. A cool air pipe 9^a leads from the register 8^a and discharges into the space between the casings 2 and 6. Otherwise, the construction illustrated in Fig. 3 is identical with that hereinbefore described.

From the foregoing, taken in connection with the accompanying drawings, it will be seen that by making certain simple improvements in a well known form of furnace, I have provided means whereby rooms which do not communicate with the originally heated rooms, may be maintained at a required temperature. This result is preferably obtained by the construction shown and described, but within the scope of the invention as claimed, numerous minor changes might well be made.

I claim:

In combination, a furnace, a register in the floor of the room above, an air heating casing around said furnace, a hot air pipe rising from the upper end of said casing

to said register and communicating with the space between said casing and said furnace, a cool air inlet casing surrounding said air heating casing and communicating therewith at its lower end, and a cool air inlet pipe surrounding said hot air pipe and leading from said register into the space between the two casings; together with a branch hot air pipe communicating with said main hot air pipe and leading therefrom to another room, said branch hot air pipe extending across the space between said cool air inlet pipe and said main hot air pipe, an additional cool air inlet pipe

leading from said last named room into the 15 space between the two casings, and a damper in said main hot air pipe pivoted above the entrance of said branch hot air pipe to swing across and close either of these pipes or to move to intermediate inclined positions. 20

In testimony whereof I have hereunto set my hand in the presence of two subscribing witnesses.

JOSEPH R. STRETESKY.
